UNITED STATES PATENT OFFICE.

ABRAHAM J. ZIV, OF CHICAGO, ILLINOIS.

DESIGN FOR A HAT.

55,837.

Specification for Design.

Patented July 13, 1920.

Application filed August 8, 1919. Serial No. 316,274. Term of patent 3½ years.

To all whom it may concern:

Be it known that I, ABRAHAM J. ZIV, a citizen of the United States, residing in Chicago, Cook county, Illinois, have invented a certain new, original, and ornamental Design for Hats, of which the following is a specification.

In the accompanying drawings, which form a part of this specification, Figure 1 shows my novel hat in side view, and Fig. 2 shows a bottom view of the hat containing my new design.

I claim:

The ornamental design for a hat substantially as shown.

ABRAHAM J. ZIV.
